CLAIM

The ornamental design for a mobile drive unit as shown and described.

DESCRIPTION

FIG. 1 is a front perspective view of a mobile drive unit. FIG. 2 is a rear perspective view of the mobile drive unit of FIG. 1.

FIG. 3 is a front view of the mobile drive unit of FIG. 1.

FIG. 4 is a rear view of the mobile drive unit of FIG. 1.

FIG. 5 is a right side view of the mobile drive unit of FIG. 1.

FIG. 6 is a left side view of the mobile drive unit of FIG. 1. FIG. 7 is a top view of the mobile drive unit of FIG. 1; and, FIG. 8 is a bottom view of the mobile drive unit of FIG. 1. The broken lines in the drawings depict portions of the mobile drive unit that form no part of the claimed design.

1 Claim, 6 Drawing Sheets
